UNITED STATES PATENT OFFICE.

EDWARD WARNER, OF WEEHAWKEN, NEW JERSEY.

FLYING-MACHINE.

1,160,473.

Specification of Letters Patent. Patented Nov. 16, 1915.

Application filed December 17, 1913. Serial No. 807,232.

To all whom it may concern:

Be it known that I, EDWARD WARNER, a citizen of the United States, residing at 326 Park avenue, in the town of Weehawken, in 5 the county of Hudson and State of New Jersey, have invented new and useful Improvements in Flying-Machines, of which the following is a specification.

My invention is of the gyropter or lifting 10 screw type, and is composed of a hollow shaft of lattice construction, with an amid-length enlargement or car, and two helicopters of opposite pitch placed to rotate in the direction of their pitch on the shaft, one 15 above the car and the other beneath it. Motive power and transmission mechanism connecting with the helicopters are provided in the car and shaft; the motor shafting and fuel being placed in one quarter-section of 20 the same, to overweight the craft in that section, and incline it from the vertical, and also, in consequence, to incline the helices of the helicopters from the mean horizontal. Through this agency the craft attains 25 its forward progress when operating in the air, and no other means are employed for that purpose. The direction of the inclination of the craft is called the forward direction, and there is ample fairway in the shaft 30 for the passage of the operator. At the lower end of the shaft, is hung a pendulum member, within which is placed mechanism to swing the same right or left, or at right angles to the inclination of the shaft; by 35 this means, the center of gravity and line of inclination of the craft may be changed laterally, and its line of travel changed accordingly. In this is contained the principle by which the craft is steered. When at 40 rest, the flying machine is in a normally suspended condition,—moored from its apex to a crane or crosshead, and from its lower end to a suitable anchorage.

The invention is fully illustrated in the 45 accompanying drawings, comprising 17 views; which are Figure 1 elevation. Fig. 2 plan viewed from above. Fig. 3 an elevation of the hubs, and a quarter-section of the out-works of the helicopters, without the webs 50 of their helices. Fig. 4 the upper portion of the lattice-shaft, of which Fig. 5, showing the amidlength car, is the lower comple- 55 tion. Fig. 6 pendulum member, that is sus- pended from the shaft, and the steering mechanism contained in the same. Fig. 7 lattice construction of the hubs of the heli-

copters. Fig. 8 plan of the car. Fig. 9 plan of the lower termination of the shaft. Fig. 10 the gearing of the power transmission mechanism, and the ball-bearings intervening between the helicopters and the shaft. Fig. 11 end view of the ball-bearings. Fig. 12 front view of the ball-bearings. Figs. 13, 14, 15, 16, and 17, illustrate the parts R, and r, components of the retaining chambers of 60 the ball-bearing mechanical units indicated in Figs. 11, and 12.

The parts are designated by letters and numbers, to which reference is made in the following detailed description.

The combination shaft and car is of lattice construction, and is formed in its mid-section by the columns V V, and in its upper and lower extensions by the columns T T, intersected by the columns t t, the 70 whole being braced by the struts c c, in the manner shown in Figs. 4 and 5. Within the midsection or car, are vertical niches and shelves, set up in the angles of its frame-work, made of the boards x x and s s, capable of holding fuel tanks and other necessities. On the shaft, two helicopters of opposite pitch are placed to rotate in opposition to each other as shown in Fig. 1. The helicopters move in ball-bearings, which are 75 illustrated in Figs. 10, 11, and 12, in the manner described in the following: There are secured to the eight columns T T, at proper spacing on the upper section of the shaft, the rings K², and K, and on those of 80 the lower section, K, and K², see Fig. 11. These rings are provided with an arc shaped slot k, near their outer rims, opposite each of the columns T T, and also with the bolt holes 2, adjacent to the slots. The length of 85 these slots may be any that will prove to be not impracticable, and for convenience may be given as three or more times the diameter of the balls 6, referred to hereafter. Each of 90 the slots k, k, forms the intermediate device 95 of a ball-bearing mechanical unit as shown in Fig. 12. A part R with a lower retaining chamber, and course for the bearing-balls 6, has an outer wall 4, with scoop-ends 3, corresponding in length and line with the slots 100 k k. The holes 5, with their edges properly rounded, pierce the bed of the part R, in line with the ends of the slots, leaving an unbroken interval between them, to serve as an axis about which the bearing-balls travel. 105 A part R is placed on the under sides of the rings K K, over each of the slots k k, of the 110

said rings. A part *r*, differing from the part *R*, only in having its retaining wall 4 on the inner side, is placed on the upper sides of the rings *K* *K*, one over each of the slots of the said rings. A capping piece *i*, grooved in true alinement with the slots *k* *k*, and to pass the bearing-balls 6, is placed over each of the said slots opposite to the parts *R* *R* and *r* *r*. All these parts as placed, are bolted to the rings, through the holes with which they are provided, corresponding to the holes 2 in the rings. The bearing-balls 6, in proper number, are placed in the courses above indicated, and travel around the axes of the parts *R* *R*, and *r* *r*, and have for counter-bearings the rings *I* *I*, and *N* *N*, to be described hereafter.

The helicopters are formed in each of their hubs, by the eight columns *M* *M*, standing severally at the angles of an octagonal plane, and are intersected near their midlength by a ring *L*, and at equal spacings by the members *m* *m*. In the upper helicopter, a ring *I*, is secured to the upper ends 20 of the columns *M* *M*, and the lower ends of said columns are secured to the ring *H*. The reverse of this order obtains in the case of the lower helicopter, see Fig. 11. The hubs are braced throughout by the struts *f* *f*. The 25 rings *H* *H*, are toothed on their inner faces, so as to engage the pinions on the power shafts, and the rings *I* *I*, are ball-bearing courses, flanged to retain the bearing-balls. All of the hub rings have outer flanges on 30 which to secure the spokes of the helicopters. From this point, the helicopters being alike in all respects excepting pitch, a description of one will serve for both. With the hub for a center, one of the helical rims *A*, rises 35 from each quarter-section of its plane, and makes substantially one complete circuit. The rims *B* *B*, parallel the rims *A* *A*, from a slightly higher plane, and at a smaller diameter, which gives the helices a parachutic curvature. The spaces between the said 40 rims are filled in with the webs *C* *C*, which are secured to the rims and can be made of sheet metal or textile fabric. The radials *D* *D*, are joined to the rims *A* *A*, in vertical 45 lines at each 24th of the circle; and beginning at the lower end of a rim *A*, the first two of the said radials, converge inwardly with the two vertically above them, meeting in what would simulate, the vertex of a 50 quadrilateral pyramid lying on its side; and this arrangement respecting these radials is continued throughout the helicopters. To 55 each of these vertices is secured, a spoke *E*, which reaches inward half the space to the hub, and is joined to a spoke *e*, which extends to the ring *L*, of the hub, and to the flange of which it is secured. The spokes *E* *E*,—*e* *e*, do not radiate from the center of the 60 helicopter, but extends tangentially to the 65 rim of its hub, and the pitch of its helices,

to enable them the better to sustain the strains imposed on them. Between the upper and lower spokes, in vertical line, and at the junctions of *E*, and *e*, are secured the 70 columns *g* *g*; which are connected, at their ends, horizontally by the members *G* *G*, making in their formation, upper and lower dodecagonal rims. There are secured at the points of junction, of the members *e* *e*, and *g* *g*, the members *F* *F*, which diverge on a 75 tangent opposite to that of the parts *e* *e*, and are secured at their other ends, to the rings, at the top and bottom of the hub of the helicopter. The columns *J* *J*, are secured to the outer ends of the spokes *E* *E*, 80 in vertical line, lying in the intermediate upper and lower planes. The columns *J* *J* with their horizontal bracings describe in outline a rectilinear cube. There are secured to the outer ends of the spokes *E* *E*, 85 the columns *d* *d*, rising from the upper ones, and depending from the lower ones, in vertical line. The helicopter has additional tensional bracings between the following points: diagonally, between the ends of 90 the members *g* *g*; diagonally between the ends of the columns *J* *J*, and horizontally between their upper and lower ends respectively; between the extreme ends of the columns *d* *d*, diagonally with their base ends,— 95 and with the holes 7, in the nearest hub ring,—also with the helices at the points *a* *a*; between the outer ends of the spokes *E* *E*, circumferentially and vertically,—also diagonally with their opposite ends, and 100 with the ends of the forward radials *D* *D*, at the points *a* *a*,—and in the case of the upper spokes, with the lower ends of the columns *g* *g*,—and in the case of the lower spokes, with the holes 7 in the lower hub 105 ring.

The flying machine is provided with a motor *A* *a*, working on the horizontal shaft *v*, secured to the frame of the car as shown in Fig. 8. To the inner end of the shaft *v*, is 110 secured a bevel pinion *Q*. The two shafts *O* *O*, extending severally up and down in the lattice-shaft, have also secured to their adjacent ends, a bevel pinion *Q*, which latter, properly mesh with the bevel pinion on 115 the shaft *v*, as shown in Fig. 5. The shafts *O* *O*, are journaled at their opposite ends in the bearings *S* *S*, in the rings *K* *K*, where they have secured to them the pinions *P* *P*. These pinions engage the toothed faces *h* *h*, 120 of the rings *H* *H*, which are adjacent to the rings *K* *K*, and are secured to the helicopters. Through the medium of the bevel gearing *Q*, the shafts *O* *O*, must always turn in opposition to each other, which opposed 125 movement they transmit to the helicopters. The pendulum member is constructed by the four columns 17, being secured at equal spacing to the circular base 18, and with their top ends secured to the ring 16, from 130

which rise fore and aft the lugs 15. The lattice-shaft has secured to its lower end the ring 10, with the brackets 12 extending from its sides, and the lugs 11 depending from it 5 fore and aft. To these lugs the pendulum member is flexibly bolted through the lugs 15, permitting it to swing from side to side.

There is also a flexible enveloping connection 14, between the lattice-shaft and the 10 pendulum, shown in outline in Fig. 6, and a ring 13 to distend the same midway. From the base 18 rises the framework 21, to which are secured the pulleys 20, and above the same the steering wheel with drum 19. 15 Around this drum is wound and secured the cable 22, which is led around the pulleys 20, to the ends of the brackets 12, to which they are secured. The pilot operating at the wheel 19, can change the center of gravity of the craft laterally, and thereby guide the same in any direction he may choose. The lattice shaft, car, and pendulum member, are enveloped in a sheathing γ , with portholes at proper locations. There is a 25 door in the pendulum, and there are lids ε at the apex of the craft, through which an attendant may moor the same to an upper support.

I claim as my invention:

30 1. In a flying machine a vertical shaft of hollow construction, affording interior passage for the operator, with bearings on the exterior of its upper and lower sections, two helicopters of opposite pitch seated one 35 above the other in the bearings on the shaft, motor and power transmission mechanism provided in the interior of the shaft, connecting with the helicopters to drive them rotatively in the direction of their pitch, 40 said mechanism installed so as to give the flying-machine a forward inclination, a pendulum member hung at the lower end of the shaft to swing from side to side at right angles to the said inclination, with 45 means within the said pendulum member to swing the same from side to side, and with means for mooring the flying-machine in a suspended condition.

2. In a flying machine, a vertical shaft of 50 hollow construction, affording interior passage for the operator, with bearings on the exterior of its upper and lower sections, two helicopters of opposite pitch seated one above the other in the bearings on the said 55 hollow shaft, a motor in a central forward position within the said hollow shaft, attached to the motor a shaft in right angle relation to the vertical hollow shaft, at the end opposed to the motor a bevel pinion attached to the motor shaft, an upper and a 60 lower bevel pinion meshing with the pinion on the motor shaft, a shaft attached to each of the upper and lower bevel pinions, the latter shafts ascending and descending respectively in a forward position 65 respectively in a forward position properly

journaled to and in vertical alinement with the hollow shaft and within the same, a gear wheel attached to each vertical power shaft at its extreme end, and a gear wheel on each helicopter meshing with the power 70 shaft gear wheel adjacent to it, a pendulum member hung at the lower end of the hollow shaft to swing from side to side at right angles to the motor shaft, with means within the said pendulum member to swing 75 the same from side to side, and with means for mooring the flying-machine in a suspended condition.

3. In a flying machine, a shaft of hollow construction affording interior passage for the operator, with ball-bearing mechanical units secured in sufficient number to the exterior of the same to afford rotary bearings for the helicopters, said mechanical units composed of steel bearing-balls coursing the same, an intermediate member with an arc shaped slot, in width a little larger than the diameter of the said balls, in length three or more times the said diameter, a member with a rounded groove, arc shaped coinciding with the said slot capping the latter on one side of the intermediate member, another member with holes coinciding with the ends of the said slot placed on the other side of the intermediate member, on the outer side of said other member a chamber arc shaped coinciding with the said slot with elliptical ends continuous of its holes, said chamber open at its outer side and at another side at right angles thereto, its depth and width being a little less than the diameter of the said balls, the course curvilinear rounded throughout for the passage of the said balls, holes for bolts in all the members comprising the course and bolts bolting them together through the same, two helicopters or lifting screws of opposite pitch placed one above the other on the hollow shaft, secured to each of the said helicopters, two rings carrying constructive ball-bearing courses suitably placed as counter-bearings to the ball-bearing mechanical units secured to the hollow shaft, a gear wheel toothed on its inner face secured to each of said helicopters in a suitable position, a motor in a central forward position within the hollow shaft, attached to the motor a shaft in right angle relation to the vertical hollow shaft, at the end opposed to the motor a bevel pinion attached to the motor shaft, an upper and a lower bevel pinion meshing with the pinion on the motor shaft, a shaft attached to each of the upper and lower bevel pinions, the latter shafts ascending and descending respectively in a forward position properly journaled to and in vertical alinement with the hollow shaft and within the same, a gear wheel attached to each of the vertical shafts at their extreme ends, said gear wheels engaging the gear

wheel of the helicopter at their respective ends of the hollow shaft, a pendulum member being at the lower end of the hollow shaft to swing from side to side at right angles to the motor shaft, with means within said pendulum member to swing the same from side to side and means for mooring the flying machine in a suspended condition.

Signed at Newark in the county of Essex and State of New Jersey this 15th day of 10 December, 1913.

EDWARD WARNER.
